US0D1050713S

(12) **United States Design Patent** (10) **Patent No.:** **US D1,050,713 S**
(45) **Date of Patent:** **** Nov. 12, 2024**

(54) **KEYRING**

- (71) Applicant: **Orbitkey Group Pty Ltd**, Port Melbourne (AU)
- (72) Inventor: **Richard Benson**, Port Melbourne (AU)
- (73) Assignee: **ORBITKEY GROUP PTY LTD**, Port Melbourne (AU)
- (**) Term: **15 Years**
- (21) Appl. No.: **29/851,626**
- (22) Filed: **Aug. 30, 2022**
- (51) LOC (14) Cl. **03-01**
- (52) U.S. Cl. **D3/207**
- (58) **Field of Classification Search**

Assistant Examiner — Caitlin A Laverty

(74) *Attorney, Agent, or Firm* — Christopher J. Knors; Moore & Van Allen PLLC

(57) **CLAIM**

The ornamental design for a keyring as shown and described.

DESCRIPTION

FIG. 1 is a perspective view of a keyring;
FIG. 2 is a front view of the keyring of FIG. 1;
FIG. 3 is a back view of the keyring of FIG. 1;
FIG. 4 is a bottom view of the keyring of FIG. 1;
FIG. 5 is a top view of the keyring of FIG. 1;
FIG. 6 is a first side view of the keyring of FIG. 1;
FIG. 7 is a second side view of the keyring of FIG. 1;
FIG. 8 is a perspective view of the keyring of FIG. 1 shown in an alternate configuration;
FIG. 9 is perspective view of the keyring of FIG. 1 shown with shading;
FIG. 10 is a front view of a keyring of FIG. 9;
FIG. 11 is a back view of the keyring of FIG. 9;
FIG. 12 is a bottom view of the keyring of FIG. 9;
FIG. 13 is a top view of the keyring of FIG. 9;
FIG. 14 is a first side view of the keyring of FIG. 9;
FIG. 15 is a second side view of the keyring of FIG. 9; and,
FIG. 16 is a perspective view of the keyring of FIG. 9 shown in an alternate configuration.

1 Claim, 16 Drawing Sheets
